George W. Miller

Attorney

UNITED STATES PATENT OFFICE.

GEORGE W. MILLER, OF WATKINS, NEW YORK.

COMBINED VENTILATOR AND DAMPER.

SPECIFICATION forming part of Letters Patent No. 377,633, dated February 7, 1888.

Application filed July 21, 1887. Serial No. 244,909. (No model.)

To all whom it may concern:

Be it known that I, GEORGE W. MILLER, a citizen of the United States of America, residing at Watkins, in the county of Schuyler and State of New York, have invented certain new and useful Improvements in Combined Ventilator and Damper; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to certain new and useful improvements in combined dampers and ventilators for stove-pipes, the object of my invention being to provide a cheap, simple, and effective means which can be employed for regulating the draft of stoves and ventilating compartments; and my invention consists in the construction and combination of the parts, as will be hereinafter fully set forth, and specifically pointed out in the claims.

25 In the accompanying drawings, which illustrate my invention, Figure 1 is a perspective view of a stove-pipe, showing my improvements applied thereto; and Fig. 2 is a vertical sectional view.

30 A refers to a stove-pipe of ordinary construction, one side of which is cut away, so as to provide an opening therein. The upper and lower edges of this opening taper toward each other to a point near the center of the pipe.

35 The opening formed in the stove-pipe is covered by a shield, B, which consists of a flat front portion, b, to which are attached the top and side pieces, b', which are preferably made of a single piece. The side pieces, b', extend

40 over the side of the pipe, and are secured to said pipe by rivets or bolts c. If desirable, the shield B may be made of a casting, so as to be formed of a single piece, and the front portion thereof projects beyond the side of the pipe A. The lower portion of the shield is left open, so that an air-passage will be provided, through which the air can pass from the compartment or room to the interior of the stove-pipe.

45 C refers to the damper, which may be semi-

circular both vertically and horizontally, the transverse diameter of the same being of about the same size as the interior diameter of the stove pipe. The damper proper is pivotally attached at its ends to pivots or bolts which are secured to the pipe, and one of said pivots has rigidly attached thereto a weighted handle, D, which will serve to hold the damper normally over the opening in the pipe, as shown in Fig. 2 of the drawings. This weighted handle or operating-bar is attached to the damper in such a position that when the damper is brought to a position shown by dotted lines, Fig. 2, the weighted operating-handle will be beyond the center and will hold the same closed. The damper may be made of malleable iron, sheet metal, or the same may be cast. The side pieces of the shield are provided with recesses d, through which the supporting pivots will pass.

55 When it is desired to use the device as a ventilating medium, the damper is turned either wholly or partially, as shown in dotted lines, Fig. 2, when the upward draft in the chimney will cause the air to be drawn through the opening in the lower portion of the shield out of the compartment or room through the stove-pipe, and when the stove-pipe is used for conveying smoke the damper will be placed in a position shown in full lines, or partially so, so as to leave the stove-pipe unobstructed. Of course the damper may be placed at intermediate positions, so as to regulate the draft and ventilate the room at the same time.

60 I am aware that prior to my invention it has been proposed to provide stove-pipes with sliding dampers, so as to form openings in the stove-pipe, and I do not claim such as my invention; but

65 What I claim as new, and desire to secure by Letters Patent, is—

70 1. In combination with a stove-pipe having an opening formed therein, a shield attached over said opening in the stove-pipe, so as to leave an opening at the lower portion of said shield communicating with the interior of the pipe, and a damper pivotally attached to the interior of the stove-pipe on a line with said shield, substantially as shown, and for the purpose set forth.

2. In combination with a stove-pipe having an opening formed therein, a shield rigidly secured thereto and provided with side and top projecting walls, and a curved damper pivotally secured within the pipe and provided with a weighted operating lever, substantially as shown, and for the purpose set forth.

In testimony whereof I affix my signature in presence of two witnesses.

GEORGE W. MILLER.
